UNITED STATES PATENT OFFICE.

CHARLES J. JOHNSON, OF CHICAGO, ILLINOIS.

NOTE-SHEET-SHIFTING MECHANISM FOR PLAYER-PIANOS.

1,188,076.

Specification of Letters Patent. Patented June 20, 1916.

Application filed January 11, 1916. Serial No. 71,450.

To all whom it may concern:

Be it known that I, CHARLES J. JOHNSON, a citizen of the United States, and a resident of the city of Chicago, county of Cook, 5 and State of Illinois, have invented certain new and useful Improvements in Note-Sheet-Shifting Mechanism for Player-Pianos, of which the following is a specification.

10 My invention relates to improvements in note sheet shifting mechanism for player pianos, and has for its object the production of mechanism of this character which will be adapted to afford means for effecting shifting of the note sheet of a player piano notwithstanding that the edges of the note sheet may be mutilated.

In pneumatically operated note sheet mechanism in use at the present time for effecting automatic shifting or adjusting of the note sheet in order to secure proper alinement of the perforations therein with the openings in the tracker bar, proper operation of the mechanism is dependent upon 25 the note sheet having unmutilated or unfayed edges. This being so in the event of a note sheet having mutilated or frayed edges being played, the pneumatic note sheet shifting mechanism will not only not serve 30 its purpose of keeping the note sheet in proper position upon the tracker bar, but will, on the contrary, serve to aggravate matters and shift the sheet to inoperative position upon the tracker bar and thus make 35 it impossible to render the selection. The above is true for the reason that all pneumatically operated note sheet mechanisms in use at the present time comprise openings in the tracker bar of the piano which are 40 adapted for engagement under the extreme edges of the note sheet, one or the other of said openings being uncovered upon shifting of the note sheet from its proper position relative to the tracker bar. Upon the uncovering of one of said openings as mentioned 45 the mechanism is automatically operated to shift the note sheet into proper position. Hence with this arrangement it is apparent that in the case of a note sheet 50 being used which has a mutilated edge, as the mutilated portion passes one or the other

of the openings in the tracker bar, the opening will be exposed, just as though the note sheet were really in inoperative position, with the result of effecting shifting of the 55 note sheet even though at the time the same may be in proper position.

The present invention aims to provide pneumatically operated means and also manually operated means for effecting shifting 60 of the note sheet together with means for rendering inoperative the pneumatically operated means, so that in the event of a note sheet having a mutilated edge being played the pneumatically operated means may be 65 rendered inoperative and only the manually operated means relied upon for effecting the shifting of the note sheet.

With these objects in view, the invention consists in the combinations and arrangements of parts hereinafter described and claimed.

The invention will be best understood by reference to the accompanying drawings forming a part of this specification, and in 75 which,

Figure 1 is a top plan view of the note sheet carrying portion of a player piano to which is applied note sheet shifting mechanism embodying the invention, Fig. 2 is 80 an end elevation of Fig. 1, Fig. 3 is a section taken on line 3—3 of Fig. 1, Fig. 4 is a section taken on line 4—4 of Fig. 1, Fig. 5 is a section taken on substantially line 85 5—5 of Fig. 1, and Figs. 6 and 7 are sections taken on lines 6—6 and 7—7 respectively of Fig. 5.

The preferred form of construction as illustrated in the drawings is used in conjunction with a player piano in which rollers 90 10 and 11 are provided for accommodating the note sheet. Between said rollers is arranged the conventional tracker bar against which the note sheet is adapted to travel in the passage of the same from one roller to 95 the other. The roller 11 is mounted to permit of longitudinal shifting of the same as is usual in order to effect shifting of the note sheet in securing proper registration of the same with the tracker bar. Such shifting 100 of roller 11 is effected by means of a shifting fork 14 which is fulcrumed at 13 the

upper end thereof engaging with a channel pulley 15 provided upon one end of the spindle of roller 11. The lower end of fork 14 is connected by means of a link 16 with a rocker arm 17 projecting from a rocker shaft 18 suitably mounted in brackets as shown. The arrangement is such as will be seen that rocking of the shifting fork 13 in order to effect the desired shifting of roller 11 is secured by simply oscillating the shaft 18.

The pneumatically operated means for effecting automatic shifting of the note sheet embodies a pair of bellows 19 and 19' each of which has a movable side 20, said sides 20 being connected by rods 21 so that the same move in unison. With this arrangement it will be seen that when one bellows is collapsed the other will be distended, and vice versa. Communicating with each bellows is an air chamber 22 which also communicates with the outside atmosphere through a passage 23 as clearly shown in Fig. 4. Provided below the chamber 22 is a vacuum chamber 24, the latter chamber being formed between members 25 and 26 which are rigidly connected together, being securely mounted upon the frame work of the player piano. In the operation of the mechanism the air is withdrawn from the chamber 24 through a pipe 24' which is in communication with a pump or other suction mechanism, not shown. The vacuum chamber 24 communicates with each of the air chambers 22 through a port 27. An angular valve head 28 is arranged in each of the chambers 22 and carries valves 29 and 30, the valve 29 being arranged to hold the corresponding port 27 normally closed and the valve 30 being arranged to close the corresponding port 23 when the valve head swings to open the port 27. Said valve head is swingingly secured in position by means of a hinge 31 formed preferably of fabric. Formed in the member 25 directly below each air chamber 22 is an intermittent vacuum chamber 32 which is separated from chamber 34 by means of a flexible diaphragm 33, each of the chambers 32 being connected by a passage 34 with a flexible tube 35, the tubes 35 communicating with the terminal openings 36 in the tracker bar 12 as will be readily understood. Provided below the member 25 as clearly shown in Fig. 7 is a bleeder vacuum chamber 37 which is in constant communication with each of the chambers 32 through minute bleeder openings 38 which communicate with the passages 34 as shown. A rod 39 is slidably mounted in a suitable bracket 40 and contacts with the corresponding diaphragm 33 and the corresponding valve 29, so that upward movement of the diaphragm 33 into the chamber 34 will raise the corresponding

valve 29 from its seat and swing the corresponding valve 30 to its seat.

In operation a vacuum is maintained in each of the chambers 24 and 32. When the note sheet is properly positioned upon the tracker bar or so that both of the openings 36 are closed thereby the status of the parts of the pneumatic mechanism, as shown, will be undisturbed. However, upon lateral shifting of the note sheet out of central position so as to effect uncovering of one of said openings 36 air will be admitted to the corresponding chamber 32 through the corresponding tube 35, thus destroying the vacuum normally maintained in said chamber 32, and causing the corresponding diaphragm 33 to be drawn upwardly toward chamber 24 by the vacuum which is maintained therein. This operates the corresponding valve 29 and closes the corresponding valve 30 so that a vacuum is also formed in the corresponding chamber 22 causing collapse of the corresponding bellows 19 or 19' with the result of moving the sides 20 of the bellows either to the right or left, as the case may be. One of the sides 20 is connected by means of a link 41 with a rocker arm 42 provided upon the shaft 18. This being so, movement of said bellows sides, as mentioned, effects rocking of the shaft 18 with the result of actuating the note sheet roller 11 to automatically shift the note sheet back to central position upon exposure of either one of the openings 36 as above described.

As before pointed out, this pneumatic means of automatically maintaining the note sheet in proper relation with the tracker bar is effective only when the edges of the note sheet are unmutilated. In order however to provide for the manual shifting of the note sheet when desired, a valve 43 is provided in the chamber 24 for closing the suction passage leading from said chamber as clearly shown in Figs. 6 and 7. The valve 43 is carried by an arm 44 which is pivotally connected with the member 25 by means of a hinge 45 of fabric. Said valve is held in open position by means of a crank 46 formed upon a stem 47 which is rockingly mounted between the members 25 and 26, the inner end thereof being mounted in a suitable bearing 48. This bearing 48 serves to hold the stem 47 against longitudinal movement in one direction, a collar 49 serving to hold said stem against longitudinal movement in the other direction. Said collar is secured to stem 47 by means of a set screw 50 the outer end of which protrudes from said collar so as to serve as a contact member adapted for engagement with stop pins 51 and 52 which limit the oscillatory movement of said stem to approximately ninety degrees. The crank 46 is adapted to engage against the

under side of the free end of arm 44, and is adapted, when in elevated position, to hold the valve 43 in open position, as will be readily understood. When it is desired to 5 render inoperative the pneumatic mechanism, it is only necessary to rotate the stem 47 so as to carry the crank 46 to horizontal position as shown in Figs. 6 and 7 whereupon, the valve 43 will drop by gravity to 10 closing position. The outer end of stem 47 projects exteriorly as seen so as to permit of ready manual engagement thereof in actuating the same.

Manual actuation of the note sheet shifting mechanism, after closing of the valve 43, is effected through a rocker arm 53 which projects from the lower end of shaft 18, said rocker arm being connected by means of a link 54 with a pivotal handle 55 which is 20 fulcrumed at 56. It will be seen that rocking of the shaft 18 and hence actuation of the note sheet shifting mechanism is effected by simply rocking the member 55.

While I have illustrated and described the 25 preferred form of construction for carrying my invention into effect, this is capable of variation and modification without departing from the spirit of the invention. I, therefore, do not wish to be limited to the 30 precise details of construction set forth, but desire to avail myself of such variations and modifications as come within the scope of the appended claims.

Having described my invention what I 35 claim as new and desire to secure by Letters Patent is:

1. In a note sheet shifting mechanism for player pianos, the combination of a pneumatically operated means for shifting the 40 note sheet; manually operated means for shifting said note sheet; and manually operable means for rendering inoperative said pneumatically operated means, substantially as described.

45 2. In a note sheet shifting mechanism for player pianos, the combination of pneumatically operated means for shifting the note sheet; manually operated means for shifting said note sheet; a valve adapted, in one position, to render inoperative said pneumatically operated means; and means for moving said valve to and holding the same in one of its positions, substantially as described.

50 3. In a note sheet shifting mechanism for player pianos, the combination of pneumatically operated means for shifting the note sheet; manually operated means for shifting said note sheet; and rockingly mounted means for moving said valve to and holding the same in one of its positions, substantially as described.

55 4. In a note sheet shifting mechanism for player pianos, the combination of pneumati-

cally operated means for shifting the note 65 sheet; manually operated means for shifting said note sheet; a valve adapted, in one position, to render inoperative said pneumatically operated means; and a rockingly mounted stem having a crank adapted to engage with said valve to move the same to and hold the same in one of its positions, substantially as described.

5. In a note sheet shifting mechanism for player pianos, the combination of pneumati- 70 cally operated means for shifting the note sheet; manually operated means for shifting said note sheet; a valve adapted, in one position, to render inoperative said pneumati- 75 cally operated means; a rockingly mounted stem having a crank adapted to engage with said valve to move the same to and hold the same in one of its positions; and means for limiting movement of said stem through an angularity of substantially ninety de- 80 grees, substantially as described.

6. In a note sheet shifting mechanism for player pianos, the combination of pneumati- 85 cally operated means for shifting the note sheet; manually operated means for shifting said note sheet; a valve adapted, in one position, to render inoperative said pneumati- 90 cally operated means; a rockingly mounted stem having a crank adapted to engage with said valve to move the same to and hold the same in one of its positions; a collar on said 95 stem for locking the same against longitudinal movement; a set screw for securing said collar to said stem; and stationary stops adapted for engagement by said set screw 100 to limit movement of said stem through an angularity of substantially ninety degrees, substantially as described.

7. In a note sheet shifting mechanism for player pianos, the combination of pneumati- 105 cally operated means for shifting the note sheet; manually operated means for shifting said note sheet; a normally closed valve, adapted when closed, to render inoperative said pneumatically operated means; and manually operated means for moving said valve to and holding the same in open position, substantially as described.

8. In a note sheet shifting mechanism for player pianos, the combination of an oscillatory member adapted, when oscillated, to effect shifting of the note sheet; pneumati- 115 cally operated means operatively connected with said oscillatory member for effecting automatic shifting of the note sheet; a manu- 120 ally operable handle operatively connected with said oscillatory member for effecting manual shifting of the note sheet; and means for rendering inoperative said pneumatically operated means, substantially as described.

9. In a note sheet shifting mechanism for player pianos, the combination of an oscillatory shaft, adapted when oscillated, to effect

shifting of the note sheet; a pair of rocker arms on said shaft whereby the latter may be operated; pneumatically operated means operatively connected with one of said rocker arms for effecting automatic shifting of the note sheet; a manually operated handle operatively connected with the other of said rocker arms for effecting manual shifting of the note sheet; and means for rendering in-

operative said pneumatically operated means, **10** substantially as described.

In testimony whereof I have signed my name to this specification in the presence of two subscribing witnesses.

CHARLES J. JOHNSON.
